John Cleazar Brown, of Chenango, New York
Letters Patent

The schedule referred to in these Letters Patent and making part of the claims containing a description in the words of the said Cleazar Brown himself of his improvement in the Machine for Threshing Wheat and other grain. To all to whom these presents shall come

Be it known that I Cleazar Brown of Chenango in the County of Broome and State of New York have invented a new and useful Threshing Machine; and that the following is a full and exact description of the construction and operation of the said machine as invented by me reference being had in said description, to the annexed drawing

Fig. 1. is a stout wooden frame about six feet high and eight feet long, a substantial panel partly enclosing each end, & a similar one passes through the centre of the frame, these panels are marked A. A hole of suitable size is cut through each panel and the trunk or cylinder D. inserted, this cylinder may be made of wood or metal and should be about three feet in diameter firmly embraced by and secured to the panels. The shaft F. has four pairs of wings placed transversely at its head marked E. and is armed with beaters or wooden pins made square and passing through the shaft at right angles or otherwise as seen at C. and may either contain some rows of pins or not, this shaft is inserted in the cylinder and the guides secured in the boxes placed on cross timbers at each end of the frame marked B.

Hence, steam or other power is applied to the drum G. which communicates an accelerated motion to the shaft by a band on the small pulley L. near the head of the cylinder and below the same is a horizontal opening to which is fixed the apron H. the operation of threshing wheat or other grain is performed by placing a sheaf upon the apron and pulling the machine through the aperture I. the rapid motion of
